US00D576559S

(12) **United States Design Patent**
Sayres et al.

(10) **Patent No.:** US D576,559 S
(45) **Date of Patent:** ** Sep. 9, 2008

(54) **FIBER TROUGH HORIZONTAL T
COMPONENT**

5,067,678 A 11/1991 Henneberger

(75) Inventors: **Derek Sayres**, Lonsdale, MN (US);
Thomas C. Tinucci, Chaska, MN (US);
Yilmaz Bayazit, St. Louis Park, MN
